UNITED STATES PATENT OFFICE

FRITZ A. ANDERSON, OF MILTON, WISCONSIN, ASSIGNOR TO THE BURDICK CORPORATION, OF MILTON, WISCONSIN, A CORPORATION OF DELAWARE

THERAPEUTIC APPARATUS

Application filed May 26, 1928. Serial No. 280,731.

My invention relates to therapeutic apparatus.

It will be illustrated and described as embodied in equipment particularly intended for use wherever large groups of persons are to be subjected to ultra violet ray treatment, such as at public health centers, gymnasiums, public schools and like institutions.

An object of the invention is to provide an improved apparatus for therapeutic light treatments.

A further object is to provide equipment in which the time during which the exposure of the patient takes place may be accurately predetermined and may be maintained constant for the successive treatment of each of a relatively large group of patients.

A further object is to provide equipment in which a large number of patients may be simultaneously treated within a relatively small compartment, thus reducing the space necessary for the installation of the device.

Another object is to provide apparatus in which the patients receive treatment while standing up so that all sides of the body are simultaneously exposed to the ultra violet rays.

A further object is to provide apparatus in which the patients may be successively exposed to the ultra violet rays, or in which exposure of a group of patients may commence and end at the same time.

Other objects and advantages will herein-after appear.

An embodiment of the invention is illustrated in the accompanying drawings, in which

Fig. 1 is a top plan of the equipment with the roof of the central compartment removed and parts thereof broken away;

Fig. 2 is an end elevation of the apparatus;

Fig. 3 is a view similar to Fig. 2 of the opposite end of the apparatus;

Fig. 4 is a sectional view along the line 4—4 of Fig. 1;

Fig. 5 is a side elevation of the apparatus with parts thereof in section;

Fig. 6 is an enlarged top plan of the power

drive and speed changing mechanism for actuating the conveyor tread; and

Fig. 7 is a side elevation of the mechanism illustrated in Fig. 6.

In general, the equipment selected for illustration comprises a compartment A, having a plurality of ultra violet ray generating lamps B arranged along its opposite side walls; a driven conveyor tread C, extending centrally through the compartment and beyond the opposite ends thereof; driving mechanism D for moving the conveyor tread; a master control station E having controlling members for regulating the intensity of lamps B and the speed of the conveyor tread driving mechanism; and approach and exit walks F and G at the opposite ends of the conveyor tread C respectively whereby patients may ascend to the level of tread C, upon which tread may stand during treatment, and may descend from the tread after treatment.

Compartment A has but two openings 10 and 11 respectively at its opposite ends through which the ends of the endless belt conveyor tread C extend. The openings 10 and 11 are sufficiently large to permit a person standing upon tread C to be moved into and out of the compartment. Sliding doors 12 are provided to close openings 10 and 11 (see Fig. 3) for a purpose hereinafter described though for ordinary operation of the equipment these doors remain open.

The floor 13 of compartment A is contiguous with the upper surface of conveyor tread C and slopes upwardly toward the side walls 14 of the compartment, as shown in Fig. 4, so that a patient standing upon tread C may not injure himself by walking off of the tread during the course of treatment. In like manner the upper ends 15 and 16 of walks F and G are contiguous with the upper surface of the conveyor tread to enable the patient to walk to and from the tread without difficulty or danger.

The ultra violet ray generating units B are preferably of the mercury arc type employing a quartz tube mercury arc lamp 18 having a curved reflector 19 at the rear so as to distribute the rays in a wide bend above the conveyor tread C. These units may be re-

placed with infra red ray generating units or any other units for generating and projecting rays beneficial to the human body, depending upon the character of treatment desired.

5 Conveyor tread C is of the endless type and comprises a plurality of laterally aligned wood slats 20 hingedly connected with one another and each having rollers 21 at their 10 pivotal connections 22. Rollers 21 ride upon two pairs of sprocket wheels 23 and 24, a pair at each of the opposite ends, respectively of the tread, and are guided in a channel 25 on the upper half of the span between sprocket wheels 23 and 24, thus maintaining the upper surface of the tread level and contiguous with the adjacent edges of floor 13. The lower span of the conveyor tread between sprockets 23 and 24 is prevented from 15 undue sagging by angle irons 25^a lying beneath and parallel to channels 25, upon which rollers 21 ride (see Fig. 4). The upper side 20 of channels 25 form a part of the floor 13.

Driving mechanism D is mounted under 25 floor 13 and is connected with the shaft 27 of sprockets 23 by a sprocket 28 mounted upon the end of shaft 27 and a drive chain 29. Chain 29 passes over a sprocket 30 on the shaft 31 of a reduction gear mechanism 32 30 having a reduction ratio of approximately 120 to 1. The driven shaft 33 of reduction gear mechanism 32 is connected by a coupling 34 to the drive shaft 35 of a speed changing transmission 36. This speed changing 35 transmission may be of the type illustrated in U. S. Patent No. 1,440,797, issued January 2, 1923, to Milton O. Reeves and comprises a driven shaft 37 interconnected by a variable friction belt drive 38 with drive 40 shaft 35 whereby the speed ratio between shafts 37 and 35 may be changed at will. A rotatable rod 39, forming a part of the transmission, actuates the friction drive to cause a change in the speed ratio between the driven 45 and drive shaft. To enable an operator standing at station G to alter the speed of conveyor tread C, a hand wheel 40 is mounted in a convenient position at station E and connected with rod 39 by a drive rod 41 and universal joints 42.

Driven shaft 37 of the speed changing mechanism has a relatively large pulley wheel 43 mounted thereon which is connected with the drive pulley 44 of an electric motor 45 50 by a belt 46.

A switch 48 mounted at station E and within convenient reach of the operator is employed to control motor 45. In order that the operator may observe the exact speed at which 55 conveyor tread C is moving, a tachometer 50 is mounted at station E and connected by a flexible drive shaft 51 with a gear 52 which is in mesh with a gear 53 carried by the driven shaft 35 of the speed changing mechanism.

60 The operation by watching tachometer 50

and adjusting the speed of the conveyor tread, by actuation of wheel 40, may accurately control the time during which a patient standing upon tread C is subjected to the rays of the ultra violet ray generating 70 units as he passes through compartment A.

The operator during operation of the equipment will stand at the station E upon a platform 50^a at the level of tread C and will start motor 45 by closing switch 38. The speed of 75 the conveyor belt or tread C is then determined by the time of exposure of the patients S during treatment and hand wheel 40 operated to adjust the speed changing mechanism 36 until the conveyor tread is moving at the 80 proper speed, as evidenced by a reading of the tachometer.

The ultra violet ray lamps B are turned on and the intensity of their illumination is 85 regulated by rheostats 52, located upon an instrument panel 53 in front of the operator at station E. Voltmeters 54 are provided so that the operator may determine the voltage impressed upon each of the lamps 18. Each of the generating units B has in its circuit a 90 switch 55, voltmeter 54 and a rheostat 52 so that one or all of the generating units may be used during treatment and each independently regulated.

After the generating units are in operation 95 the patients S will mount entrance walk F and stand sidewise upon the moving tread C with their backs toward one of the walls 14 of the compartment and facing the opposite wall. A metal railing 60 is mounted at one 100 side of entrance walk F and exit walk G and platform 50^a to guard against falling from the walks and platform while walking or standing thereupon or stepping to and from the conveyor. Fig. 2 illustrates the manner 105 in which patients S mount the entrance walk F and stand upon tread C and Fig. 5 illustrates a group of patients standing upon the tread simultaneously receiving treatment. Arrow 61 indicates the direction of travel of 110 tread C. The patient at the extreme left will be the first one to be moved out of compartment A to a point in registration with the exit walk G, whereupon he will descend the walk to the floor level. The patient at the 115 extreme right and standing upon tread C is about to be moved into the compartment where his treatment by exposure to the ultra violet rays will commence.

If a second and longer exposure to the rays 120 is to be administered at a later date, as is the usual course in periodical treatment, the speed of tread C is decreased by operation of speed changing mechanism 36 in the manner described and the patient will then remain 125 within the compartment a relatively longer time due to the slower motion of the tread.

While my improved apparatus is primarily intended for the treatment of a large number 130 of patients successively admitted to the mov-

ing tread and subjected to the ultra violet rays, the solarium may also be used to simultaneously treat a small group, the treatment for all starting and ending at the same time.

5 Where this course of treatment is to be followed, the conveyor tread will remain at a stand-still and the patients will walk upon the tread and stand within the compartment. Thereupon the operator may maintain the 10 ultra violet ray generating units in operation for a time sufficient to result in the desired exposure. Doors 12 during this time may be closed if desired and opened at the end of the treatment so that the patients may walk 15 out through the exit door 11 and descend walk G. Another group may be in readiness for similar treatment and in a position at entrance walk F to walk upon the tread.

Having thus illustrated and described the 20 nature and one embodiment of my invention, what I claim and desire to secure by United States Letters Patent is as follows:

1. Therapeutic apparatus comprising a compartment, a radiant energy generator 25 within the compartment, an endless moving belt-like tread by which patients may be moved through the compartment in the path of rays emitted by the radiant energy generator, and means for controlling the treatment, said means including a controller for 30 varying the speed of the belt tread to vary the time a patient is subjected to the rays, and a controller for varying the intensity of the emission of the radiant energy generator.

35 2. Therapeutic apparatus comprising a compartment, a radiant energy generator within the compartment, an endless belt-like tread by which patients may be moved through the compartment in the path of rays 40 from the radiant energy generator, a drive for said tread, and a controller for varying the speed of the tread to control the duration of treatment by controlling the time a patient is passed through the compartment in 45 the path of the rays.

3. Therapeutic apparatus comprising a compartment, a radiant energy generator within the compartment, an endless belt-like tread for supporting and carrying patients 50 through the compartment in the path of the rays emitted by the generator, and a variable speed drive for moving and controlling the speed of the belt-like tread to vary the duration of treatment by varying the time required for a patient to be carried through 55 the compartment in the path of the rays.

4. Therapeutic apparatus comprising a compartment, a radiant energy generator within the compartment, a movable platform 60 for carrying patients through the compartment in the path of the rays emitted by the radiant energy generator, a source of power for moving the platform, and a controller for varying the speed of the platform to 65 control the duration of treatment by con-

trolling the time a patient is subjected to the rays.

5. Therapeutic apparatus comprising a compartment, a radiant energy generator within the compartment, a movable platform 70 for carrying patients through the compartment in the path of the rays emitted by the radiant energy generator, and a source of power connected to move the platform so as to carry a patient through the path of the 75 rays in the time required for one treatment.

In witness whereof, I hereunto subscribe my name this 22 day of May, 1928.
